MUSICAL CARD GAME

Filed August 21, 1924

FIG. 1.

FIG. 2.

BY

INVENTOR:
Henry F. Gilbert
Clyde L. Rogers
his ATTORNEY

UNITED STATES PATENT OFFICE.

HENRY F. GILBERT, OF CAMBRIDGE, MASSACHUSETTS.

MUSICAL CARD GAME.

Application filed August 21, 1924. Serial No. 733,300.

This invention relates to a musical card game that may be termed "musical solitaire," the interest and central feature of which depends on a capability of arranging individual musical measures borne by the respective cards in a multiplicity of different sequences so that musical periods of different characters may be produced therefrom at will by selectively arranging different series of cards of the deck in juxtaposition. In carrying out my invention I provide a deck of cards which may be generally similar to ordinary playing cards and of a number to make up a deck of convenient size, e. g., about sixty cards, and provide different musical measures extended inward from certain or all of the edges of the cards with an aligned arrangement whereby selected cards may be arranged in an over-lapping series to make a continuous musical period that may be set up in different ways at will according to the arrangement of the cards. In carrying out my invention I preferably produce measures in different times extending in from the respective edges of the several cards so that musical periods written in such different times may be set up at will.

Since a musical period usually embraces eight measures, the cards are designed so as to be arranged in a corresponding overlapping series, eight in number, to make up a complete period. Such musical period of eight measures embodies two phrases of four measures each, the first of which is called the antecedent and the second the consequent phrase. The antecedent phrase usually starts the melody on one of the notes of the chords of the tonic of the key in which it is written, and ends upon the fourth measure with a pause or punctuation mark or so-called semicadence. The consequent phrase follows, usually beginning on the same beat with which the antecedent began, and ending with a perfect cadence upon an accented beat of the final or eighth measure with the tonic note or a note of the chord thereof thus acting as a conclusion of the tune or melody and with a character of finality about it which would be out of place in any of the other measures of the melody. It will, therefore, be understood that the fourth and eighth measures of the period must be specially constituted with reference to the foregoing requirements, and I therefore, produce a part of the cards, e. g.,

about twelve of the sixty with measures especially adapted for serving as the fourth measure of the period and marked with a distinguishing character e. g. the number 60 four (#4). I also produce a number of the cards e. g. about eight of the sixty with measures specially adapted for the end of the consequent phrase, i. e., to complete the melody and mark these also with a distinguishing character e. g. the number eight (8). The foregoing and other objects and advantages of the invention will more fully appear from the following detailed description taken in connection with the accompanying drawings, and the distinctive features of novelty will be pointed out in the appended claims.

Referring to the drawings:

Fig. 1 is a plan view showing a series of 75 eight cards embodying my invention arranged in an overlapping sequence to produce a selected musical period.

Fig. 2 is a plan view of one of the cards especially designed for the fourth measure 80 or end of the antecedent phrase; and

Fig. 3 is a plan view of one of the cards for the first and intermediate measure, or any one except the fourth and eighth.

The cards 10, of which there are preferably sixty in number, though there may be more or less as desired within the contemplation of the invention, bear each musical measures 11, 12, 13, 14 extending inward from the respective edges thereof. These measures are preferably written in different times, e. g., the measure 11 extending inward from one edge being illustratively shown as in two-four (2/4) time, the measure 12 from another edge in three-four (3/4) time, the measure 13 from another edge in four-four (4/4) time and the measure 14 from the fourth edge in six-eight (6/8) time. Certain of the cards have these measures especially arranged to constitute the end of the antecedent phrase or fourth measure of the period and these may be marked with the character 4 as seen in Fig. 2, while others of the cards which are especially designed to constitute the end 100 of the consequent phrase and conclusion of the period may be marked with the distinctive number eight (#8) as seen at the right of Fig. 1. In practising the game, selected cards are laid in over-lapping relation as 105 seen in Fig. 1 so as to expose the desired melody measure extending in from one edge

thereof and concealing the other measure on the card by the over-lapping of the next card as indicated at 15, and thus exhibiting a continuous sequence of aligned measures as indicated at 16. In thus setting up the musical period the melody may be varied at will by selecting different sequences of cards, care being only taken to insure that one of the cards marked "4" shall be fourth 10 in the series, and one of the cards marked "8" shall be eighth or last in the series. I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to 20 indicate the scope of the invention.

Having described my invention, what I claim as new and desire to secure by Letters Patent is:

1. A musical card game, comprising a 25 deck of cards each having a musical measure extending inward from certain or all of the edges thereof and adapted to be placed in over-lapping relation to constitute a musical sentence or period, certain of said cards being distinctively marked to denote them for the fourth measure of the period, and others of said cards being distinctively marked to denote them for the eighth measure of the period.
2. A musical card game, comprising a 30 deck of cards each bearing musical measures extending inward from the edges thereof, said cards adapted to be selectively arranged in over-lapping relation to constitute a complete musical period or sentence.
3. A musical card game, comprising a 35 deck of cards each bearing a single musi-

cal measure extending inward from each of the respective edges thereof and adapted to be placed in juxtaposition so that the 45 series of measures constituted by consecutive cards constitute a complete musical period or sentence, certain of said cards having distinctive markings to denote them for the fourth measure of the period, and others of said cards having distinctive markings to denote them for the eighth 50 measure of the period.

4. A musical card game comprising a deck 55 of cards each bearing musical measures extending inward from edges thereof, said cards adapted to be interchangeably arranged in over-lapping relation to constitute a complete musical period or sentence, certain of said cards having distinctive markings to denote them for the fourth 60 measure of the period, and others of said cards having distinctive markings to denote them for the eighth measure of the period.

5. A musical card game comprising a deck 65 of cards each bearing musical measures extending inward from the edges thereof, said cards adapted to be interchangeably arranged in over-lapping relation to constitute 70 a musical period or sentence, certain of said cards having distinctive markings to denote a pause in the melodic sentence.

6. A musical card game comprising a 75 deck of cards each bearing a musical fragment or melodic particle extending inward from the respective edge portions thereof, said cards adapted to be interchangeably arranged in over-lapping relation to constitute a musical period or sentence.

In testimony whereof, I have signed my name to this specification.

HENRY F. GILBERT.
